(57) **CLAIM**

The ornamental design for an architectural panel, as shown and described.

DESCRIPTION

FIG. 1 is a perspective view of an architectural panel showing our new design;

FIG. 2 is a front elevational view thereof;

FIG. 3 is a left elevational view thereof;

FIG. 4 is a right elevational view thereof;

FIG. 5 is a top elevational view thereof;

FIG. 6 is a bottom elevational view thereof; and,

FIG. 7 is a perspective environmental view thereof.

The broken lines in the drawings represent portions of the architectural panel that form no part of the claimed design.
